INVENTOR:
Lawrence Guldaman
ATTORNEYS.

UNITED STATES PATENT OFFICE.

LAWRENCE GULDAMAN, OF HOBOKEN, NEW JERSEY.

ASH-CAN OR THE LIKE.

1,359,057.

Specification of Letters Patent. Patented Nov. 16, 1920.

Application filed September 8, 1920. Serial No. 408,668.

To all whom it may concern:

Be it known that I, LAWRENCE GULDAMAN, a citizen of the United States, residing at Hoboken, in the county of Hudson and State of New Jersey, have invented or discovered certain new and useful Improvements in Ash-Cans or the like, of which the following is a specification, reference being had therein to the accompanying drawing.

This invention relates to cans for holding ashes, garbage or the like, and has for its object to provide an improved construction whereby a can of this character will be protected from being battered or indented when handled roughly or dropped violently on the ground or pavement. To this end the invention comprises a series of cushioning springs which are attached to the bottom of the can and bent loosely around the bottom flange of the can and then extended upward over the sides of the can in such a manner that the sides will be protected against indentations when the can is being dumped over the edge of a collecting wagon, and the bottom of the can will be protected from injury when the can is dropped violently on the ground or pavement.

In the accompanying drawing Figure 1 is a sectional elevation of the improved can, and Fig. 2 is a bottom view thereof. Fig. 3 illustrates a slightly modified form of the invention. Fig. 4 is a detail view of one of the brackets at the top of the can shown in the form of the invention illustrated in Fig. 1, and Fig. 5 a detail view of one of the side brackets of the can.

Referring to the drawing, 12 denotes the body of the can and 13 the bottom thereof. To a flat ring or disk 14 on the bottom of the can is attached, by riveting or otherwise, a series of radial springs 15 which are bent loosely around the flange 16 at the bottom of the can and are extended up to form side springs 17 which are loosely connected with brackets 18 attached to the sides of the can, as by rivets 19 extending through slots 20 in the outer faces of the brackets 18. The rivets 19, in the construction shown, are held in place by small plates 21 riveted to the side springs 17 and the inner heads of the rivets 19 will be formed thereon after the rivets have been passed through the slots 20 and before the brackets 18 are riveted to the can body 12.

In the form of the invention shown in Fig. 1 the upper ends of the springs 17 are loosely and slidably connected to the top of the can by small brackets 22 riveted to the top of the can and underneath which the upper ends of the said springs 17 are free to move to a limited extent.

The springs 15 are so constructed as normally to spring away from the bottom 13 of the can, as shown in Figs. 1 and 3, so as to hold the loops 15^a at the bottom of the can free from or below the lower edge of the flange 16. The said loops are loosely connected to the said flange by means of rivets 23 which are free to have a limited sliding movement in slots 24 formed in the said flange 16.

In the construction shown in Fig. 3 the vertical side springs 17 are riveted to the top of the can and are loosely connected with brackets 18 by rivets 19 as in the construction shown in Fig. 1.

From the foregoing it will be understood that the invention comprises not only means for protecting the sides of the can, as has been heretofore proposed, but also means for protecting the bottom of the can when roughly handled or dropped to the pavement, the jar or shock of the impact, in such case, being absorbed or cushioned by the spring loops 15^a.

Having thus described my invention I claim and desire to secure by Letters Patent:

1. A can, for the purpose indicated, comprising a series of springs attached to the bottom thereof and loosely bent around the flange at the bottom of the can, said springs extending upwardly along the sides of the can and being connected with the top of the latter.

2. A can, for the purpose indicated, comprising a series of springs attached to the bottom thereof and loosely bent around the flange at the bottom of the can, said springs extending upwardly along the sides of the can and being connected with the top of the latter, combined with brackets attached to the sides of the can and with which brackets the said springs are loosely connected.

3. A can, for the purpose indicated, comprising a series of springs attached to the bottom thereof and loosely bent around the flange at the bottom of the can, said springs extending upwardly along the sides of the

can and being connected with the top of the latter, combined with brackets attached to the sides of the can and with which brackets the said springs are loosely connected, and with brackets attached to the top of the can with which the said side springs are also connected.

4. An ash can or the like having a bottom flange, combined with a series of radial springs at the bottom of the can and having loops loosely connected with said flange.

In testimony whereof I affix my signature.

LAWRENCE GULDAMAN.
